UNITED STATES PATENT OFFICE.

JOHN BALLEMBERGER AND CHARLES SCHEIDEMANTEL, OF PITTSBURG, PENNSYLVANIA.

HOSE-COUPING.

SPECIFICATION forming part of Letters Patent No. 749,253, dated January 12, 1904.

Application filed May 18, 1903. Serial No. 157,699. (No model.)

To all whom it may concern:

Be it known that we, JOHN BALLEMBERGER and CHARLES SCHEIDEMANTEL, citizens of the United States of America, residing at Pittsburgh, in the county of Allegheny and State of Pennsylvania, have invented certain new and useful Improvements in Hose-Couplings, of which the following is a specification, reference being had therein to the accompanying drawings.

This invention relates to certain new and useful improvements in hose-couplings, and has for its object the provision of novel means whereby two sections of a hose may be easily, quickly, and effectually coupled together.

Another object of our invention is to provide a hose-coupler which will be comparatively inexpensive to manufacture, strong and durable, and highly efficient in use.

Briefly described, our invention comprises a male and female member, the male member of which carries a tubular projection which snugly fits into a recess formed in the female member of the hose-coupling. The male member has secured to its sides a yoke which engages over the female member and securely holds the same in position.

In describing the invention in detail reference is had to the accompanying drawings, forming a part of this specification, and wherein like numerals of reference indicate like parts throughout the several views, in which—

Figure 1 is a side elevation of our improved hose-coupler. Fig. 2 is a longitudinal sectional view thereof. Fig. 3 is a detail perspective view of the male member. Fig. 4 is a detail perspective view of the yoke constituting the locking means.

To put our invention into practice, we provide a male member 1, which carries the tubular extension 2, said tubular extension engaging in a recess 3 formed in the female member 4. These members carry a central aperture 5 and have their ends knurled or grooved, as indicated at 6, to receive the hose-section. The male member 1 has its body portion 7 cut away on the top and under side, as indicated at 9, said cut-away portion forming shoulders 10.

The sides of the body portion 1 are cut away 50 at the angles 11 and 12, forming beveled surfaces over which engage the beveled sides 14 of the yoke 15. This yoke is secured pivotally, as indicated at 16, to the body portion 17 of the female member. The yoke 15 carries the 55 side arms 18, which have apertures 19 formed in their outer ends, whereby they are secured to the body portion 17, as indicated at 16. Formed integral with the yoke 15 and extending outwardly therefrom is the handle or operating-lever 20. When our improved hose-coupler is in the coupled position, as shown in Fig. 1 of the drawings, the beveled sides 14 of the yoke engage over the beveled surfaces 11 of the body portion 7 of the male 60 member, the yoke 15 resting in the cut-away portion 10 formed in the top face of the body portion.

The manner of coupling our improved hose-coupler is as follows: The tubular extension 70 2 of the male member is inserted into the recess 3 formed in the female member 1, when the yoke 15 is drawn downwardly, the side arms 14 engaging over the beveled faces 11 of the body portion, this operation forcing 75 the tubular extension farther into the recess until the same has been seated. In the side arms 14 we form the cut-away portion 21, which engages over the apex of the two beveled surfaces 11 and 12, as indicated at 22, thereby 80 locking the two sections of hose together. In case it is desired to reverse the yoke 15 we employ the beveled surfaces 12, whereby the same may be used in a similar manner to the beveled surface 11. 85

While we have herein shown and described our invention in detail, it is obvious that we do not care to limit ourselves to the exact construction, as various slight changes may be made therein without departing from the general spirit of our invention. 90

Having fully described our invention, what we claim as new, and desire to secure by Letters Patent, is—

A hose-coupling comprising a male and female member, the first-named member carrying an extension normally received in the last-named member, the body portion of the 95

first-named member being cut away on its top and bottom to form shoulders, the sides being cut away to form inclined portions meeting centrally of said sides in the shape of a **V**, 5 a locking member comprising a pair of side arms pivoted to the female member and a yoke straddling the male member, the sides of said yoke being inclined to conform to the inclined portions of the male member, and 10 being notched adjacent the upper end of the yoke-arms, said inclined faces of the arms engaging said inclined portions, of the male member and receiving the apex of the **V** in said notches, and an operating-lever secured

to the cross-bar of the yoke and extending 15 in a direction opposite to the sides thereof, whereby said yoke may be actuated downwardly to bring the notches of the sides thereof into engagement with said apex of the **V**-shaped portions of the male member. 20

In testimony whereof we affix our signatures in the presence of two witnesses.

JOHN BALLENBERGER.
CHARLES SCHEIDEMANTEL.
